TRIPLE-ACTION BLAST FURNACE
GAS WASHER

Isaac E. Sheward, Youngstown, Ohio

Application August 4, 1947, Serial No. 765,920

4 Claims. (Cl. 183—24)

1

This invention relates to a triple-action blast-furnace gas-washer.

An object of this invention is the construction of a highly efficient gas-washer, which will be free from corrosion caused by flue dust and chemical reaction within the washer itself.

Another object of the invention is the construction of a simple and efficient washer which will remove the vapor, mist and sludge that has been impossible to accomplish in the washer heretofore, resulting in an unsatisfactory deposit in the gas mains.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Fig. 1 is a view in side elevation of an apparatus constructed in accordance with the present invention, while

Fig. 2 is partly a vertical section and partly an elevation of the same.

Fig. 3 is an enlarged, fragmentary vertical sectional view of the apparatus.

Fig. 4 is an enlarged, vertical sectional view of part of the apparatus.

Fig. 5 is a top plan view of the apparatus.

Fig. 6 is a horizontal sectional view taken on line 6—6, Fig. 3, and looking in the direction of the arrows.

Fig. 7 is a horizontal sectional view taken on line 7—7, Fig. 4, and looking in the direction of the arrows.

Fig. 8 is a horizontal sectional view taken on line 8—8, Fig. 4, and looking in the direction of the arrows.

Referring to the drawings, in which the preferred embodiment of this invention is illustrated, 1 designates the primary casing of this washing apparatus, which casing is provided with a dome 2. Within the casing 1 is a primary tile checker work 3, below which is a funnel-shape, primary water-seal 4. The water-seal 4 is composed of a number of plates fastened together and communicating said seal 4 is a water-seal 5, as seen in Fig. 3. Extending vertically through the checker work 3 and the water-seal 4 are a plurality of tile-lined tubes 6. These tubes open at the top near dome 2.

A gas-main 7 is provided with a goose-neck 8 extending into casing 1 between the checker work 3 and the water-seal 4. Extending into the casing 1 and through the dome 2 are a plurality

2

of sprayers 9; these sprayers each have a suitable nozzle, and discharge inwardly within casing 1.

The water-seal 4 and 5 has a discharge pipe 10 connected to its lower end, and said discharge pipe 10 empties into a discharge pipe 11; discharge pipe 11 is open at its upper end, for the efficient operation of the apparatus.

Extending into casing 1 are second sets of sprayers 12; these sprayers 12 discharge under the water-seal 4 and upon the secondary checker work 13; this secondary checker work 13 has a semi-funnel-shape baffle plate 14. The checker 13 is more clearly shown in Fig. 3.

In the primary checker work 3 and the secondary checker work 13 are linings, against the inner face of casing 1, and also around tubes 6. These linings comprise a shell of cement 15, and between shell 15 and casing 1 is a lining of copper 16; this is also true of the construction enclosing each of the tubes 6. The checker work 3 is supported upon I-beams 17.

Under the secondary checker work 13 is a dryer 18 which has a dome 19, and a baffle 20. Said dryer 18 is also provided with laterally-extending outlets 21, Fig. 2.

A baffle 22 is under baffle 20 with an apron 23 thereon. A catch-basin 24 is below the apron 23. This catch-basin 24 is provided with a series 30 of substantially V-shape bottom portions 25 that produce four V-shape compartments, each compartment has a drain-tube 26 communicating therewith, and each drain-tube 26 extends into the auxiliary water-seal 27, Fig. 2. The auxiliary 35 water-seal 27 is provided with a discharge-pipe 29, which pipe 29 communicates with the lower end of the water-seal 27. The outer end of pipe 29 communicates with pipe 30, which is open at its top, and is similar to pipe 11.

40 The gas enters the casing 1 through the gas-main 7 and goose-neck 8, said goose-neck being flattened out and of suitable shape at its junction with the casing or washer, so that the gas strikes the surface of the water-seal 4 at a downward angle and is spread out over the entire surface of the seal 4, and passes around the pipes 6.

45 The gas then passes up through the checker work 3, striking the dome 2 and is deflected downward through the four tubes 6, which must extend ten feet above the checker 3. The dome 2 houses the spray system, which consists of

50 many sprayers 9 with suitable nozzles arranged so as to saturate all checker work surfaces. The gas enters the washer at a downward angle and strikes the surface of the water-seal

and a percentage of the flue-dust is precipitated. The gas rises through the checker 3 and is saturated and cooled by the dome sprays 9 before being deflected by the dome and passing down through the four tubes 6. The water from the sprayers 9 passes through the checker work 3 washing and precipitates from the checker work surfaces. This warm, dirty water drains into the water-seal 4 and is discharged through pipes 10 and 11. About 98 per cent of the flue-dust will be eliminated in this first operation.

The waste water from the blast-furnace cooling-system (not shown) can be used in this first action by use of an ordinary booster pump. From two million, five hundred thousand to three million gallons of water in a 24-hour period is recommended for the first operation just described, depending upon how badly the furnace is dusting.

In the next step of operation, the flue-dust is carried over in three forms, to wit: Mist, vapor, and slush. As the gas emerges from the tubes 6 into the space between the water-seal 4 and checker work 13, it comes into contact with the water sprays. The cool water condenses the vapor at this point. By having the gas and water both travel in the same course (downward), the break-down of the mist is started. The slush is deposited on the surface of the checker work as it endeavors to pass through. The water flowing through the checker work dissolves this slush into a solution and carries it off as such.

The gas and water passes through the checker 13 and strikes the baffle-plate 14, which deflects the water inward, by reason of its peculiar structure, onto the top of the dryer 18, thence to the baffle plates 20 and 22. As the water flows from the lower edges of these plates, it forms a solid sheet of water through which the gas must force its way, losing and breaking down whatever slush, vapor and mist remain in it.

The apron 23 is attached to the lower edge of the baffle 22 for the purpose of directing the water into the catch-basin 24 through the tubes 26, thence into the second water-seal 27, from where it is discharged through discharge pipes 29 and 30. The gas at this point frees itself from the water (all water at this point is in a drop form) and flows toward the outer shell, then downward to the surface of the water-seal 27, from which this is deflected upward into the dryer 18, Fig. 4, through the opening between the catch-basin 24 and the water-seal 27. The gas entering the large mouth of the dryer 18 loses velocity, allowing the remaining water to settle out. The gas rises through the dryer 18 and is discharged through the two six-foot gas-mains 21.

The water flowing over the top and sides of the dryer will cause the dryer to have a condensing action; for this reason the water should be as cool as is possible. One million, five hundred gallons of water per 24-hour period is recommended for this action. Therefore, this washing apparatus in its operation, as has just been described, will remove the vapor, mist and sludge that other washers pass through and deposit in the gas mains.

It is also recommended that the pump (not shown) for the dome sprays 9 have a capacity of two hundred thousand gallons per hour. Also, it should have an automatic control (situated in the gas main as close to the blast-furnace as is practicable), so that in case of a furnace slip, the water pressure will be increased so as to take care of the abnormal amount of dust coming through

the apparatus at this time. This increased water pressure should be maintained for a short time after the slip is over. The pump (not shown) should have a manual pressure control set for the most efficient operation.

The gas at the bottom of the apron 23 goes out to the casing 1 and down to the bottom of the dryer and passes between the catch-basin 24 and the water-seal 27. The water goes into the catch-basin 24 and is discharged through the four discharge pipes 26 into the water-seal 27 at the bottom.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination of a casing provided with a dome top, a primary water-seal in said casing, a checker work above said water-seal, means discharging gas into said casing between said water-seal and checker work, pipes extending through said checker work and said water-seal, sprayers connected to said dome top and discharging into said casing, a second checker work under said water-seal, a dryer provided with outlets under said auxiliary checker work, a catch-basin around said dryer, an auxiliary water-seal under said catch-basin, and means connecting said catch-basin to said auxiliary water-seal.

2. In an apparatus of the class described, the combination of a casing provided with a dome top, sprayers extending through said top, a primary checker work under said dome top, a funnel-shape water-seal under said checker work, vertical tile-lined tubes extending through said checker work and water-seal, each tube being open at both ends, a secondary checker work under said water-seal, said secondary checker work provided with a funnel-like baffle-plate, a dryer extending up in said baffle-plate and being positioned within said casing, said dryer including a dome-like top, said dryer provided with laterally-extending pipe-like outlets, said dryer provided with a baffle at said outlets, said dryer provided near its middle with a secondary baffle having a depending apron, said last-mentioned baffle and apron being spaced from said dryer, a catch-basin formed around the dryer at its lower end, said catch-basin being provided with raised bottom portions producing compartments, each compartment provided with a depending tube, an auxiliary water-seal closing the bottom of said casing and positioned under said catch-basin, said tubes extending into said auxiliary water-seal, and sprayers extending through said casing between said primary checker work and said first-mentioned funnel-shape water-seal.

3. In an apparatus of the kind described, a vertically extending casing having a dome-shaped top, a V-shaped partition in the upper part of said casing, tubular members extending vertically from said partition and terminating adjacent said dome, said tubular members opening through said partition and having open upper ends, checker work surrounding said tubular members and engaging the inner face of said casing, a water seal filling the partition around the lower ends of said tubular members, the water level of said seal being spaced below said checker

work, a multiplicity of water jet nozzles carried by said dome and directing water downwardly against the upper surface of said checker work, supply means for flue gas opening into the casing between said checker work and water seal, a secondary checker work spaced below said partition and forming a second partition in said casing, a second multiplicity of water jet nozzles extending into said casing between the first mentioned partition and the secondary checker work, said last jet nozzles being arranged to direct water onto the upper surface of said secondary checker work, and a mist condenser and water collecting means in the casing and aligned directly below said secondary checker work.

4. In an apparatus of the kind described, a vertically extending casing having a dome-shaped top, a V-shaped partition in the upper part of said casing, tubular members extending vertically from said partition and terminating adjacent said dome, said tubular members opening through said partition and having open upper ends, checker work surrounding said tubular members and engaging the inner face of said casing, a water seal filling the partition around the lower ends of said tubular members, the water level of said seal being spaced below said checker work, a multiplicity of water jet nozzles carried by said dome and directing water downwardly against the upper surface of said checker work, supply means for flue gas opening into the casing between said checker work and water seal, a secondary checker work spaced below said partition and forming a second partition in said casing, a second multiplicity of water jet nozzles extending into said casing between the first mentioned partition and the secondary checker work, said last jet nozzles being arranged to direct water onto the upper surface of said secondary checker

5
